UNITED STATES PATENT OFFICE.

EDWARD O. BABCOCK, OF NIAGARA FALLS, NEW YORK.

MACHINE FOR MAKING PAPER-BOARD.

1,143,931.

Specification of Letters Patent. Patented June 22, 1915.

Application filed April 2, 1913. Serial No. 758,323.

To all whom it may concern:

Be it known that I, EDWARD O. BABCOCK, a citizen of the United States, residing at Niagara Falls, in the county of Niagara and 5 State of New York, have invented a new and useful Improvement in Machines for Making Paper-Board, of which the following is a specification.

This invention relates to machines for 10 making paper or pulp board or the like from pulp in a liquid or plastic state or other similar material. In machines of this character the pulp is usually formed into a web which is compressed to squeeze the moisture 15 out of it and form a compact sheet or board of the desired thickness. The pulp may be formed into a single web or into a plurality of webs which may be brought together and united into a single sheet by the compressing 20 devices.

In paper board machines as heretofore constructed, it has been customary to compress the soft pulp web by means of successive pairs of squeezing rolls until the web 25 has been reduced to the desired thickness. The usual rolls for this purpose have been open to certain objections, however, particularly in the making of thick board. The action of the squeezing rolls is necessarily to 30 produce a comparatively abrupt reduction in thickness of the web, the sharp deflection in the surface of the webs caused by the rolls resulting in a tearing apart of the fibers and a breaking of the continuity of the web 35 surface. This greatly weakens the board and is particularly objectionable when a heavy board having a low grade filling material is being manufactured, as in such a board the strength is mainly in the outer layers which 40 are most injured by the action of the rolls.

The present invention provides an improved means for squeezing or compressing the pulp web which consists in the use of converging surfaces between which the pulp 45 web is passed. These surfaces may be either stationary or movable (as by being formed upon endless traveling belts) and are preferably of such extent and inclination as to gradually and evenly compress the pulp web 50 from its initial thickness to the ultimate thickness desired for the board. By this arrangement the difficulties incident to the use of squeezing rolls are entirely eliminated.

The present invention also comprises improvements in the means for flowing the 55 pulp upon the traveling aprons of the ma-

chine, and in the arrangement of the aprons for forming a multiple ply board. It also comprises certain other improvements, the nature of which will appear from the following detailed description.

In the accompanying drawings, Figure 1 is a side elevation of a machine embodying a preferred form of the invention. Fig. 2 is a central sectional elevation thereof. Fig. 3 is a plan view thereof, the flow boxes being omitted. Fig. 4 is a detached vertical section, partly in elevation, of the compressing device. Fig. 5 is a fragmentary plan view of the compressing device on a still larger 70 scale. Fig. 6 is a sectional elevation thereof on line 6—6, Fig. 5. Fig. 7 is a fragmentary perspective view of one of the flow boxes. Fig. 8 is a transverse sectional elevation on line 8—8, Fig. 1.

A represents the frame of the machine upon which the various parts of the apparatus are mounted and which comprises two upright side portions *a a'*. This frame may be of any other suitable or desired construction.

The liquid or plastic pulp is deposited on 85 endless aprons or screens *B B'*, which pass over driving rolls or cylinders *b b* and idler rolls or cylinders *b' b'* which are suitably journaled in the frame of the machine and which convey the pulp to the compression devices. These aprons, as shown in the drawings, are made of thin sheet metal and are perforated so as to allow the excess moisture in the pulp to drain off through the perforations. Aprons of other material, such as wire or textile fabric, may be employed, if desired, and other suitable means may be provided for actuating the aprons. A layer 90 of pulp is deposited upon each of the aprons, the layer deposited on the upper apron being carried over the drum *b'* and brought into contact with the layer upon the lower apron to form a multiple ply board. The pulp is 100 of such consistency at this time, however, that the two plies firmly unite under pressure, so that there is no danger of the board splitting.

The pulp is deposited on the aprons *B B'* 105 in any suitable manner, preferably by means of a plurality of flow boxes *C*, which are arranged transversely over the aprons. The boxes are secured to the lower extremities of feed chutes or conveyers *C'*, for example by 110 means of bolts *c'*, as shown in Fig. 7. The lower ends of the feed chutes are enlarged

and enter into the flow boxes adjacent to the walls thereof. The material flows from the chutes into the flow boxes and then upwardly in the space between the enlarged ends c of the chutes and the outer walls of the flow boxes, and then down the walls of the boxes to the apron. By thus causing the material to overflow both sides of the flow boxes, two layers or plies of pulp are formed 10 by each box, and each box performs the function of two pulp feeding devices of the kind heretofore used. The flow of the pulp to the apron can be regulated by means of plates c^2 which are arranged within the 15 chutes C' and adjustable vertically toward and from stationary plates c^3 , secured to the bottoms of the flow boxes, to control the flow of pulp to the outer walls of the flow boxes. Any suitable means may be employed for 20 adjustably securing the plates c^2 to the chutes, for example, bolts c^4 , engaging with the plates c^2 and passing through slots c^5 in the side walls of the chutes.

Any number of flow boxes and feed chutes 25 may be employed, three being shown in the drawings for each apron. By means of this arrangement of the feed chutes, different grades of pulp can be used in making the board, for example, the boxes which form 30 the outer layers or plies of the board can be supplied with a long fibered pulp which will produce a tough surface, while an inferior grade of pulp may be used in the other boxes for the inner layers of the board. If it is 35 desired to make a thick board, a hopper D can also be provided which is adapted to supply to the machine a cheaper grade of pulp which forms the filler or inner ply of the board. Since this filling material is 40 usually not sufficiently liquid to flow evenly over the surface of the apron, a spreading roller d is preferably used, which spreads the material discharged from the hopper D evenly over the surface of the better grade 45 material deposited on the apron. This roller is adjustable toward and from the apron B' by means of adjusting screws d' , engaging in threaded holes in the frame of the machine and engaging bearing blocks d^2 50 slidably mounted in slots or guide openings d^3 in the frame of the machine.

E represents suitable deckle straps or belts which are located at the edges of the aprons and which move with the aprons and pass 55 over suitable pulleys e which are suitably journaled in the frame of the machine. Movement is imparted to the deckle straps by the aprons with which they are pressed into frictional engagement.

60 Means are preferably provided for removing a portion of the moisture from the pulp before the same reaches the compressing device. For this purpose suction or exhaust boxes F are preferably employed, which are 65 located on the under side of the apron and

withdraw moisture from the pulp through the perforations in the apron. The suction boxes are arranged between the flow boxes, so that a considerable portion of the moisture is withdrawn from the pulp deposited 70 by one flow box before the pulp on the apron reaches the next flow box. By this arrangement a thicker board can be made and sufficient moisture is removed from the pulp to cause the same to adhere to the lower run of 75 the upper belt. These boxes, as shown, are all connected with pipes f from which air and moisture are exhausted by any suitable means, (not shown). The means for compressing the pulp web formed by the united 80 layers of pulp deposited on the aprons B and B' so as to thoroughly consolidate the layers, squeeze the water out of the pulp and form a compact and solid paper board, are preferably constructed as follows: 85

Two plates G G' are secured to the frame of the machine, one above the other between which the aprons B B' pass. The opposing faces g g' of these plates converge in such a manner that the web of pulp, on being 90 drawn between the plates by the aprons, is gradually reduced in thickness and compressed until the desired degree of compactness is attained. Any suitable means may be employed for facilitating the movement 95 of the pulp web and the aprons through the compression device, as for example, the construction illustrated in which the plates G G' are surrounded by traveling belts H H' . Each of these belts comprises a plurality of flat plates or boards h extending transversely of the machine and secured at their opposite ends to links h' h' . These links are connected to form chains at opposite sides of the belt which are adapted to 100 pass over sprocket or notched wheels h^2 h^2 secured to shafts h^3 h^4 which pass through the opposite ends of the upper plate G and to the shafts h^5 and h^6 which pass through the lower plate G' . The belts pass around 105 the plates in opposite directions and enter the space between the plates at the widest part thereof. In order to permit the moisture to drain from the pulp while the same is compressed between the plates G G' , the 110 boards are provided with grooves or recesses h^7 extending lengthwise of the machine, in which the moisture can collect on being expressed from the pulp through the perforations in the aprons. If desired anti-friction 115 devices may be introduced between the plates G G' and the belts H H' . As shown a series of rollers I is provided which are connected by links i to form chains or belts which pass around the plates G G' underneath the belts H H' . Any other suitable means may be employed for reducing the friction between the belts and the plates. 120 The lower plate G' , in the construction shown, is rigidly secured to the frame of 125

130

the machine while the upper plate G is adjustably mounted in such manner as to permit it to be moved toward and from the lower plate, so as to regulate the compression of the pulp web and determine the thickness of the paper board. Any suitable means may be employed to effect this adjustment, for example, the upper plate may be provided at its rear end with a shaft K extending through the plate transversely of the machine and having its ends journaled in blocks k which are slidably mounted in vertical slots or openings k' in the sides of the frame. The blocks can be moved downwardly in the slots by means of adjusting screws k², passing through threaded holes in the frame and bearing on the upper faces of the blocks. In order to permit the adjustment of the plate relatively to the shaft k³ a slot k³ is formed in the plate through which the shaft k³ is adapted to pass. The front end of the plate is adapted to be adjusted by means of screws L engaging in lugs l formed on the frame of the machine. The lower ends of the screws are rotatably secured in sleeves l' which support the ends of the shaft k⁴. By the construction just described it will be seen that the relative inclination of the plates, as well as the distance between them, can be adjusted so that the extent of compression and the ultimate thickness of the board can be regulated as desired.

Any suitable means may be utilized to drive the various parts of the machine which require to be actuated. As shown, power is transmitted in any suitable manner to a pulley M which is mounted on a shaft m journaled in the frame of the machine. A pinion m' mounted on the shaft m drives a gear m² secured on a shaft m³, and a pinion m⁴ on this shaft drives a gear m⁵ mounted on the shaft h⁵. The gear m⁵ meshes with a similar gear m⁶ mounted on the shaft h³, so that these two shafts are driven in opposite directions to drive the belts H H' by means of the sprocket wheels h² as heretofore described. The opposite ends of these shafts are provided with sprocket wheels m⁷ m⁸, which are connected by chains m⁹ m¹⁰ to sprocket wheels m¹¹ m¹² for turning the driving rolls b b, over which the aprons B B' pass. It will be understood that the aprons B B' and the belts H H' need not all be positively driven from the source of power as the frictional engagement of these members may in some cases be relied upon to actuate some of the members from the others which are positively driven. For example, the aprons B B' only may be driven, their engagement with the belts H H' serving to actuate the latter, or the belts only may be driven and their engagement with the aprons utilized to cause the necessary movement thereof. Moreover, it will be understood that belts or movable surfaces for either or both of the plates G G' are not essential, but that the aprons B B' may be caused to slide directly over the converging surfaces of the plates. On the other hand the plate as such may be dispensed with if the belts H H' are made of such construction that they cannot bend or sag between their supporting pulleys and if they are of sufficient strength and rigidity to withstand the pressure necessary to properly compress the pulp web.

The operation of the machine is as follows:—The pulp is fed to the aprons B B' by the flow boxes, which can be adjusted, as described, to control the amount of pulp discharged and the thickness of the pulp web. A considerable part of the moisture is removed from the pulp by the suction boxes, so that when the upper apron B passes around the roll b', the pulp will adhere to the apron and form the upper portion of the paper board. As the aprons carrying the pulp pass between the plates G G', the two films or coats of pulp on the aprons are pressed together, the filler discharged from the hopper D, if used, being incorporated between them. The plates h⁵ of the belts form substantially unbroken flat surfaces which converge as the belts pass between the plates, so that the pulp in passing between the belt is gradually and uniformly compressed. Abrupt changes in the thickness of the web are thus avoided and injury to the surface fibers of the web is prevented. By adjusting the upper plate G toward or from the lower plate and by regulating the discharge of pulp from the flow boxes, any desired thickness of board or paper may be produced. A dense or solid board may be formed by bringing the ends of the plates together at the point of outlet and increasing the inclination of the plates, thereby making it possible to compress a comparatively thick web of pulp into a much thinner sheet. By adjusting the plates to a more nearly parallel relation, a softer and more porous board is produced. The plates and the belts running over them may be of any desired length so as to produce as great a degree of compression and to make such compression as gradual as may be deemed advisable. The compression surfaces are preferably substantially plane, though they may in some cases have a slight curvature. As will be understood, a plurality of the compression devices may be used in series if desired, or the improved compression device may be used in connection with squeezing rolls.

I claim as my invention:

1. In a compressing machine, the combination

- 5 nation of a pair of stationary plates having adjacent converging faces, endless belts surrounding said plates, friction rollers interposed between said belts and the converging faces of the plates, aprons arranged to pass between said belts and to carry the material to be compressed between the converging faces of said plates, means for driving said belts, rolls over which said aprons pass and which are adapted to impart movement to the aprons, and a driving connection between said means for driving the belts and said rolls to cause said aprons to be positively driven at the same speed as said belts.
- 10 2. In a compressing machine, the combination of a pair of stationary plates having adjacent converging faces, a pair of aprons arranged one above the other and adapted to pass between the converging faces of said plates, the lower run of the upper apron being supported adjacent to the upper run of the lower apron, means for driving the aprons to cause said runs to travel in the same direction, means for depositing pulp on the upper run of each apron, and means for pressing the lower run of the upper apron and the upper run of the lower apron toward each other to consolidate the layers of pulp on said aprons.
- 15 3. In a compressing machine, the combination of a pair of stationary plates having adjacent converging faces, a pair of aprons arranged one above the other and adapted to pass between the converging faces of said plates, the lower run of the upper apron being supported adjacent to the upper run of the lower apron, means for driving the aprons to cause said runs to travel in the same direction, means for depositing pulp on the upper run of each apron, and means for pressing the lower run of the upper apron and the upper run of the lower apron toward each other to consolidate the layers of pulp on said aprons, and means for depositing a filler on the layer of the pulp on said lower apron but before the consolidation of said layers.
- 20 4. In a compressing machine, the combination of a pair of plates having adjacent converging faces, means for adjusting said plates relatively toward each other to vary the distance between said converging faces, an endless belt surrounding one of said plates, a shaft and means connected therewith for driving said belt, said shaft extending through a slot in the plate around which said belt passes, whereby the plate is movable independently of the shaft.
- 25 5. In a compressing machine, the combination of a pair of plates having adjacent converging faces, means for adjusting said plates relatively to each other to vary the distance between said converging faces, end-
- less belts surrounding said plates, shafts for driving said belts, and means connecting said shafts to cause the same to drive both belts at the same speed, said shafts extending through said plates, at least one of said plates having a slot through which the shaft extends to permit one plate to be adjusted relatively to the other plate without changing the distance between said shafts.
- 30 6. In a compressing machine, the combination of a pair of plates having adjacent converging faces, means for adjusting said plates relatively to each other to vary the distance between said converging faces, endless belts surrounding said plates, driving shafts extending through said plates at one end thereof and adapted to impart movement to said belts, means connecting said shafts to cause the same to drive both belts at the same speed, driven shafts journaled at the other ends of said plates, at least one of said plates having a slot through which the shaft extends to permit one plate to be adjusted relatively to the other plate without changing the distance between said shafts.
- 35 7. In a machine of the character described, the combination with a traveling apron, of a flow box extending transversely thereof for depositing pulp thereon, said flow box having an upright wall at each side thereof over which the pulp is adapted to flow onto the apron, whereby each flow box forms two plies, and means for supplying pulp to the interior of the flow box.
- 40 8. In a machine of the character described, the combination with a traveling apron, of means for depositing pulp thereon, comprising a chute, and a flow box attached to the end of the chute and extending transversely of the apron, said flow box having an upturned flange at each side thereof over which the material is adapted to flow onto the apron, whereby each flow box forms two plies.
- 45 9. In a machine of the character described, the combination with a traveling apron, of means for discharging pulp thereon comprising a chute and a flow box attached to said chute, said flow box having upright outer and intermediate walls, the end of said chute having a wall projecting downwardly between said walls of the flow box, and a movable gate attached to the chute and adjustable toward and from the intermediate wall of said flow box to regulate the discharge from the latter.
- 50 Witness my hand, this 25th day of March, 1913.
